Primary Examiner — Brett Miller*Assistant Examiner* — Rani J Abdallah(74) Attorney, Agent, or Firm — Ziegler IP Law Group, LLC(57) CLAIM

The ornamental design for a cosmetics bottle, as shown and described.

DESCRIPTION

FIG. 1 is a perspective view of a cosmetics bottle showing the new design, the cosmetics bottle being shown in a closed state;

FIG. 2 is a perspective view of the cosmetics bottle of FIG. 1 shown in an open state;

FIG. 3 is a front view thereof;

FIG. 4 is a back view thereof;

FIG. 5 is a side view thereof;

FIG. 6 is another side view thereof;

FIG. 7 is a top view thereof; and,

FIG. 8 is a bottom view thereof.

The broken lines in the drawings form no part of the claimed design.

1 Claim, 8 Drawing Sheets(56)
